[57] CLAIM

The ornamental design for an electrical equipment cabinet, as shown and described.

DESCRIPTION

FIG. 1 is a front perspective view of an electrical equipment cabinet showing my new design;
FIG. 2 is a front view thereof on a reduced scale;
FIG. 3 is a back view thereof on a reduced scale;
FIG. 4 is a bottom view thereof on a reduced scale.
The side view opposite FIG. 3 is similar to FIG. 3.
The back view is plain.

FIGS. 2 and 3 are shown broken-away for convenience of illustration.

FIG. 1

FIG. 2

FIG. 3

FIG. 4
